UNITED STATES PATENT OFFICE.

ELMER F. BLISS, OF SCHENECTADY, NEW YORK, ASSIGNOR TO GENERAL ELECTRIC COMPANY, A CORPORATION OF NEW YORK.

RELAY.

No. 851,795.

Specification of Letters Patent.

Patented April 30, 1907.

Application filed August 17, 1906. Serial No. 331,002.

To all whom it may concern:

Be it known that I, ELMER F. BLISS, a citizen of the United States, residing at Schenectady, in the county of Schenectady and State of New York, have invented certain new and useful Improvements in Relays, of which the following is a specification.

My invention relates to track-relays for block-signal systems, and its object is to arrange such relays so that the number of turns in the track winding may be adjusted in a simple manner. It is desirable that all the track relays in a block-signal system should be identical in construction; but if the length of the blocks varies greatly, it is also desirable that the number of turns in the track winding of the relay should vary for different lengths of block,—particularly if alternating-current is used for the signal circuits. Since with alternating-current the impedance of the rails is comparatively high, so that the difference in impedance between a short and a long block is comparatively great. Identity of construction of the relays, and at the same time a proper proportioning of the number of turns of the relay winding for the length of block may be obtained if the number of turns in the track winding is made adjustable. By my invention this adjustment of the number of turns may be obtained without the use of flexible leads and with a minimum number of leads and contacts.

My invention consists in bringing leads from the terminals and from intermediate points of the track winding on the relay and connecting these leads to contacts arranged on two intersecting arcs, and providing two movable contacts arranged to move over the two arcs, respectively. The number of turns between each pair of adjacent leads is preferably different from that between any other pair. This arrangement, as will appear from the following description, gives a great number of adjustments with a very small number of leads and contacts.

The adjustment of the relay winding should preferably be made before the relays are installed, and should not be altered by the inspector in charge of the relay. Consequently, the contacts and leads, as above described, are preferably arranged within the casing of the relay and the pivoted contacts connected to binding posts outside the cas-

ing. The casing may then be sealed after the proper adjustment has been made, and tampering of the adjustment thereby prevented.

My invention will best be understood by reference to the accompanying drawing, in which

Figure 1 shows a plan view of a relay arranged in accordance with my invention; and Fig. 2 is a diagram of the connection.

In Fig. 1, A represents the supporting base of insulating material, on which is mounted the cover B, which is shown in cross-section in Fig. 1, which is preferably of glass, and which forms, together with the base, a casing for all the moving parts of the relay. I have illustrated a relay of the two-phase induction type, since my invention is particularly advantageous in connection with alternating-current relays; but it will be understood that my invention is not limited to this particular type of relay. C represents a pivoted conducting disk carrying the movable contacts D D'. E represents the track winding of the relay, which is mounted on a laminated magnetic core F, the poles of which extend close to the disk C on the opposite sides of the disk. G G represent coils, which are supplied independently of the track circuit with current displaced ninety degrees in phase from the current flowing through the track winding E. The coils G G are mounted on laminated cores H, the poles of which face each other on opposite sides of the poles of the core F, so as to produce two fluxes threading the disk on opposite sides of the flux produced by the track winding E. These two fluxes being ninety degrees out of phase produce a torque on the disk in the well-known manner. The connections of the two-phase relay, above described, are well understood in the art, and form no part of my invention.

The track winding E is provided with leads e, both from its terminals and from intermediate points. To these leads are connected contacts I' to I⁴, which are arranged on two intersecting arcs, as clearly shown in Fig. 2. Two pivoted contacts J J' are arranged to move over the two arcs, respectively, and are connected to binding-posts K K outside the casing. The number of turns between each pair of adjacent leads e preferably differs from that between any

other pair, as indicated in Fig. 2. For instance, if the track coil contains 360 turns, as indicated in the figure, one lead may be brought out 120 turns from one end, and the other lead 160 turns from the other end. With such an arrangement six different adjustments may be obtained with the four leads and two movable contacts shown. For instance, if contact J engages contact I^1 and contact J^1 engages contact I^2 , the entire 360 turns of the track coil will be connected between the binding-posts K K. Now, if contacts J is moved to contact I^4 and contact J^1 is moved to contact I^3 , 240 turns will be included in circuit; if contact J is moved back to contact I^1 and contact J^1 is moved to contact I^3 , 200 turns will be included in circuit; if contact J is moved to contact I^3 and contact J^1 back to contact I^2 , 160 turns will be in circuit; if contact J is on contact I^1 and contact J^1 is on contact I^4 , 120 turns are in circuit; and if contact J is on contact I^4 and contact J^1 is on contact I^3 , 80 turns are in circuit. Thus, with only two intermediate leads and two pivoted contacts, six different adjustments are secured. Furthermore, the contacts are all inclosed within the casing, so that when the adjustment is once made the casing may be sealed and alternation in the adjustment prevented.

What I claim as new and desire to secure by Letters Patent of the United States, is,

1. In a relay, a winding having leads from its terminals and from intermediate points, contacts arranged on two intersecting arcs connected to said leads, and two pivoted con-

tacts adapted to move over the two arcs respectively.

2. In a relay, a winding having leads from its terminals and from intermediate points, the number of turns between each pair of adjacent leads being different from that between any other pair, contacts arranged on two intersecting arcs connected to said leads, and two pivoted contacts adapted to move over the two arcs respectively. 45

3. In a relay, a casing, a winding therein having leads from its terminals and from intermediate points, contacts within the casing arranged on two intersecting arcs and 50 connected to said leads, two pivoted contacts within the casing adapted to move over the two arcs respectively, and binding-posts outside the casing connected to said pivoted contacts. 55

4. In a relay, a casing, a winding therein having leads from its terminals and from intermediate points, the number of turns between each pair of adjacent leads being different from that between any other pair, 60 contacts within the casing arranged on two intersecting arcs and connected to said leads, two pivoted contacts within the casing adapted to move over the two arcs respectively, and binding-posts outside the casing connected to said pivoted contacts. 65

In witness whereof, I have hereunto set my hand this 16th day of August, 1906.

ELMER F. BLISS.
